MITCHELL L. FYKSE, OF SOUTH MILWAUKEE, WISCONSIN.

CARBURETER.

1,158,324.

Specification of Letters Patent. Patented Oct. 26, 1915.

Application filed August 19, 1912. Serial No. 715,711.

To all whom it may concern:

Be it known that I, IVAN M. SMITH, a citizen of the United States, residing at South Milwaukee, county of Milwaukee, and State 5 of Wisconsin, have invented new and useful Improvements in Carbureters, of which the following is a specification.

My invention relates to improvements in carbureters.

10 The object of my invention is to provide a form of carbureter in which the fuel delivery may be regulated by the entering air currents in such a manner as to approximately maintain the proper proportions of 15 fuel and air delivery to the mixing chamber.

A further object of my invention is to provide means whereby the fuel delivery in approximately proper quantity will not be dependent upon the maintenance of a constant level of oil in the supply chamber or 20 reservoir.

A further object of my invention is to provide means whereby fuel delivery during periods when the engine is not in operation 25 will be absolutely prevented.

In connection with the foregoing objects, my invention contemplates suitable means for varying the proportionate quantities of fuel and air delivered in accordance with 30 the requirements for different kinds of work.

In the drawings, Figure 1 is a sectional view of a carbureter embodying my invention, drawn to a plane cutting the axes of fuel and air inlets and mixture outlet. Fig. 35 2 is a half plan view of a portion of a carbureter embodying my invention. Fig. 3 is a sectional view, drawn on line $x-x$ of Fig. 1. Fig. 4 is a sectional view, drawn on line $y-y$ of Fig. 1. Fig. 5 is a rear end 40 elevation partially broken away to show the turbine or impact motor, the auxiliary air inlet portion of the casing being omitted. Fig. 6 is a partial elevation of the opposite or front end of my improved carbureter.

45 Like parts are identified by the same reference characters throughout the several views.

The casing 1 of my carbureter is formed to provide a mixing chamber 2 having an outlet at 3, which communicates with the cylinder of an internal combustion motor. A tubular member 5 extends across the central portion of the mixing chamber, and is provided with a nozzle 6 through which the 55 fuel may be delivered to said chamber. The

tubular member 5 is enlarged near its front end and a valve 8 is adapted to seat upon the shoulder 10 formed by the enlargement of the member 5. A spring 12 is interposed between the valve 8 and an exterior cap 13, 60 which covers the projecting end of the tubular member 5, this spring serving to automatically seat the valve 8 when the latter is not otherwise held open. Liquid fuel is conveyed from any suitable source of supply through a duct 14, which delivers it through cap aperture 15 to the space occupied by the spring 12.

A cylindrical slide valve 18 is mounted in the tubular member 5 and is provided with 70 a fuel delivery slot 19, adapted to move into and out of registry with the nozzle cavity 48 communicating with the nozzle 6. The cylinder 18 is hollow and ducts 20 lead inwardly from its front end, whereby liquid 75 passing the valve 8 will be permitted to enter this cylinder and to pass from the cylinder through the elongated port or slot 19 to the nozzle 6 when the cylindrical valve is in a position with the slot in registry with 80 said nozzle cavity 48.

The cylindrical slide valve 18 is actuated by means of a rotary turbine wheel or impact motor 25, the hub of which is secured to an internally threaded feed nut 26, having 85 threaded engagement with a valve actuating stem 27. Said valve actuating stem preferably extends through the cylindrical slide valve 18, and has a screw threaded portion 28 in threaded engagement with the front 90 end portion of said valve 18, as clearly shown in Fig. 1. The valve 18 is held against rotation by a key 29. With this construction, it is obvious that a rotation of the turbine wheel 25 in one direction will 95 cause the stem 27 to move forwardly as the feed nut 26 rotates with the wheel 25. A rotation of wheel 25 in the other direction will of course retract stem 27.

Air is admitted to the mixing chamber 2 100 through inlets at 35, which direct the incoming air against the vanes 36 of the turbine wheel 25. The impact of the air upon the vanes 36 causes wheel 25 to rotate in a direction to move the slide valve 18 forwardly 105 as above explained, and as soon as this air current ceases to flow through the ports 35, the turbine wheel is rotated backwardly by the reaction of the spiral spring 40, which spring is wound upon and connected with 110

the hub of the turbine wheel, with its outer end connected to a worm wheel 41, by which the tension of the spring 40 may be adjusted. The worm wheel 41 may be actuated from the exterior by means of a worm shaft 42 provided with a knob 43. A set screw 44 may be employed to lock the worm shaft in any desired position of adjustment. By varying the tension of the spring 40, the degree of rotation of wheel 25 may be controlled.

In normal position, the slot 19 may be wholly out of registry with the nozzle 6, or its front end may extend to the nozzle cavity 48 so as to permit the delivery of a slight quantity of fuel to said cavity 48 in the wall of the member 5, thus allowing a delivery of a small quantity of fuel to the nozzle with the valve in this position. When the valve is moved forwardly, however, the fuel delivery is increased in proportion to the area of the slot 19, which is brought in registry with the nozzle cavity 48. It is therefore obvious that as the velocity of the air through the air inlet ports is increased, the rotation of wheel 25 will be proportionately increased, thus moving the valve 18 forwardly a correspondingly greater distance and uncovering a greater area of the feed slot or port 19.

A ring valve member 50 encircles that portion of the casing which is provided with the air inlet ports 35. This ring valve member is provided with stationary vanes 51 and intervening air ports 52, which, when in registry with the ports 35, allow the air to pass to the vanes 36 of the turbine. When the ring 50 is adjusted to open the air ports, a segmental shoulder 55 carried by the ring is utilized to actuate rod 56, pushing the latter inwardly through the valve stem 27 to actuate the main valve 8 to open position. The segment 55 actuates push rod 57. This bears at its rear end upon a set screw 58 carried by a lever 60 which is pivoted to the rear wall of the casing with one arm in position to bear upon the rear end of said push rod 56. The spring 63 restores lever 60 to normal position, when segment 55 is out of registry with the rod 57, thus allowing valve 8 to close under the pressure of spring 12.

The casing 1 is provided with a water circulation cavity 70, and is also provided with an auxiliary air admission port at 71, normally closed by a spring actuated valve 72, which opens only under excessive suction or under manual pressure.

Assuming all the ports to be in normal position, with main valve 8 closed and the annular air valve ring 50 also in a position to close the air ports 35, it is obvious that neither fuel nor air can be delivered. By rotating the air valve 50 to uncover air ports 35, the main valve 8 will be opened through

the medium of segment 55 engaging the end of rod 57 and forcing the latter backwardly to actuate lever 60 and rod 56. Liquid fuel will then be permitted to flow past valve 8 to the interior portions of member 5 and through the ducts 20 to an annular channel 75 in the sleeve stem 27 of this valve, from which the liquid may pass through that portion of the slot 19 which is in registry with the nozzle cavity 48. It is therefore obvious that a small quantity of fuel may thus be delivered to the nozzle. If suction be then applied in the engine cylinder, a current of air will enter through ports 35, actuating the turbine wheel 25, and the rotation of the latter will be communicated through the feed nut screw to actuate the valve stem 27 and move the valve 18 inwardly, thus increasing the exposed area of valve port 19, with a corresponding increase in liquid delivery proportionate to the volume of air entering through the ports 35. It is of course not essential that the slot port 19 should be located to deliver any liquid to the nozzle cavity 48 when the valve 18 is in its normal position, but it will be found that better results will be secured by allowing for a slight delivery of liquid to the nozzle in advance of the initial air delivery.

With the described construction, the liquid delivered through the nozzle may be so accurately regulated by the valve 18, having a long narrow port 19 controlled as to position by the turbine, that ordinary variations in the level of the liquid fuel delivered through the duct 14 may be disregarded. In case of extraordinary variations or in case of radical differences in the density of the liquid fuel employed at different times, the oil delivered may be easily regulated by means of the worm shaft 42 used for adjusting the tension of spring 40, the degree of turbine wheel rotation being thus controlled.

Referring to Figs. 3 and 4, it will be observed that the slot port 19 is not formed in the main body of the slide valve cylinder 18, but that said cylinder is provided with a removable section 80, in which the slot port 19 is located. This feature, however, is purely structural and is adopted with a view to accuracy and convenience in forming the slot port.

I claim—

1. The combination with a carbureting chamber provided with an air inlet and a mixture outlet, of a tubular member crossing said chamber and projecting into the air inlet, said member constituting a fuel inlet, a nozzle communicating with said member and projecting laterally from the member in the direction of the outlet, a rotary impact motor located in the air inlet, a valve controlling the delivery of liquid fuel from said tubular passage into the nozzle and

connections between said impact motor and valve.

2. The combination with a carbureting chamber provided with an air inlet and a mixture outlet, of a tubular member crossing said chamber and projecting into the air inlet, said member constituting a fuel inlet, a nozzle communicating with said member and projecting laterally from the member in the direction of the outlet, a rotary impact motor located in the air inlet, a valve controlling the delivery of liquid fuel from said tubular passage into the nozzle and connections between said impact motor and valve, said impact motor and chamber wall constituting an air inlet passage and said passage being provided with a manually adjustable throttle valve.

3. The combination with a carbureting chamber having air and fuel inlets and a mixture outlet, of a tubular non-rotatable slide valve controlling the fuel inlet, a screw threaded valve stem, and a rotary member in the path of the air from the air inlet, adapted to be actuated by the air and carrying a feed nut in threaded connection with said valve stem.

4. The combination with a carbureting chamber having air and fuel inlets and a mixture outlet, of a slide valve controlling delivery through the fuel inlet, a valve stem, an air driven turbine located in the air inlet in feed screw connection with the stem, and means for automatically moving the valve toward closing position during the intervals between periods of air delivery, said turbine being operatively connected to open the valve during air delivery.

5. The combination with a carbureting chamber having air and fuel inlets and a mixture outlet, of a non-rotatable valve controlling delivery through the fuel inlet, an air actuated rotary member in the path of air entering through the air inlet, said rotary member being held against longitudinal movement, a feed screw connection between the rotary member and valve adapted to open the valve in direct proportion to the air delivery past the rotary member, a spring adapted to retractively rotate the rotary member, and means for manually regulating the delivery of air to said chamber.

6. The combination with a carbureting chamber having air and fuel inlets and a mixture outlet, of a tubular member connected with the fuel inlet and provided with a nozzle within said chamber, a main valve controlling the delivery of fuel to said chamber, a tubular slide valve within said mem-

ber, provided with a slotted port and controlling delivery of fuel to the nozzle, an air driven turbine adapted to actuate the slide valve, a manually actuated air valve controlling the air inlet, and means, connected therewith, for opening said main valve simultaneously with the opening of the air valve.

7. The combination with a carbureting chamber having air and fuel inlets and a mixture outlet, of a tubular member connected with the fuel inlet and provided with a nozzle cavity and nozzle within said chamber, a non-rotatable slide valve having a slotted port and controlling the delivery of fuel to said nozzle, and an air actuated turbine driven by air entering through the air inlet for automatically adjusting said slide valve to secure a progressively increasing registry of said slot with the nozzle cavity in proportion to the increase in quantity of air delivered.

8. The combination with a carbureting chamber having air and fuel inlets and a mixture outlet, of a tubular member connected with the fuel inlet and provided with a nozzle cavity and nozzle within said chamber, a slide valve having a slotted port and progressively controlling the delivery of fuel to said nozzle, means controlled as to valve opening movements by the velocity of the air entering through the air inlet, for adjusting said slide valve, and means for automatically closing said valve when air delivery ceases, together with a main valve for shutting off the supply of fuel to the tubular member.

9. The combination with a carbureting chamber having air and fuel inlets and a mixture outlet, of a tubular member connected with the fuel inlet and provided with a nozzle within said chamber, a slide valve having a slotted port and progressively controlling the delivery of fuel to said nozzle, and means controlled by the velocity of the air entering through the air inlet, for adjusting said slide valve, together with a main valve for shutting off the supply of fuel to the tubular member, an air valve, and connections between the air valve and main valve adapted to transmit motion from one to the other.

In testimony whereof I affix my signature in the presence of two witnesses.

IVAN M. SMITH.
